(57) **CLAIM**

The ornamental design of a portion of a wheel hub, as shown and described.

DESCRIPTION

FIG. 1 is a front elevational view of the portion of a wheel hub according to our design; and,

FIG. 2 is a perspective view thereof from the front and left side.

Throughout the Figures, broken lines showing structure are for illustrative purposes only and form no part of the claimed design.

1 Claim, 2 Drawing Sheets

FIG. 1

FIG. 2
